[57] CLAIM

The ornamental design for a conduit spacer, as shown and described.

DESCRIPTION

FIG. 1 is a front elevational view of a conduct spacer showing my new design;

FIG. 2 is a side elevational view thereof, the view of the side opposite is substantially a mirror image thereof; and FIGS. 3 and 4 are respectively top and bottom plan views thereof.

FIG. 2

FIG. 3

FIG. 1

FIG. 4
